UNITED STATES PATENT OFFICE.

GEORGE J. COUTU, OF LOWELL, MASSACHUSETTS.

FIRE-EXTINGUISHING APPARATUS.

1,074,165.

Specification of Letters Patent.

Patented Sept. 30, 1913.

Application filed June 14, 1911. Serial No. 633,159.

To all whom it may concern:

Be it known that I, GEORGE J. COUTU, a subject of the King of Great Britain, residing at Lowell, in the county of Middlesex and State of Massachusetts, have invented certain new and useful Improvements in Fire-Extinguishing Apparatus, of which the following is a specification.

This invention relates to fire extinguishing apparatus, and more particularly to an improved water tower.

The invention aims primarily to provide a water tower designed to throw a number of streams of water in different directions into a burning building, in which respect it differs from the ordinary water tower which is only adapted to throw a stream of water upon the roof or against the walls of a building.

20 To this end, the tower of the present invention includes a water supply pipe which is adapted to have its discharge end projected into a burning building through one of the windows thereof, the pipe at its said 25 end being provided with a number of nozzles presented in different directions so as to throw a number of streams of water in different directions.

One novel feature of the invention resides in means which is provided for raising and lowering the support for the pipe above mentioned, and means for advancing and retracting the pipe so that it may be projected through any window of a burning building.

The invention also contemplates the provision of means for tilting the pipe so that different portions of the room in which the discharge end of the pipe is projected, may 40 be more or less thoroughly flooded as found necessary.

For a full understanding of the invention reference is to be had to the following description and accompanying drawings in 45 which:—

Figure 1 is a perspective view of the apparatus embodying the present invention, in use. Fig. 2 is a side elevation of the apparatus collapsed. Fig. 3 is a perspective view of the mechanism for adjusting the water supply pipe, the supports for the elements of this adjusting means being omitted. Fig. 4 is a front elevation of a portion of the apparatus, the water supply pipe and several other parts being shown in section. Fig. 5 is a vertical sec-

tional view on the line 5—5 of Fig. 4, looking in the direction indicated by the arrows. Fig. 6 is a similar view on the line 6—6 of Fig. 4. Fig. 7 is a horizontal sectional view on the line 7—7 of Fig. 5. Fig. 8 is a detail view of the discharge end of the water supply pipe. Fig. 9 is a fragmentary view similar to Fig. 6.

Corresponding and like parts are referred to in the following description and indicated in all the views of the accompanying drawings by the same reference characters.

In the drawings, the apparatus is illustrated as mounted upon a wheeled truck the frame of which is indicated by the numeral 1 and the supporting wheel by the numeral 2. This truck is preferably motor driven although it may be drawn by horses if preferred, and it is of a length to accommodate the apparatus when in collapsed condition, as illustrated in Fig. 2 of the drawings. At the forward end of the truck frame there is fixed a base 3 upon which 70 is mounted a circular track 4. A platform 5 is provided upon its under side with wheels 6 which travel upon the track 4, and the platform is in this manner mounted for rotation, it being held against tilting by 75 a shaft 7 which is secured axially therethrough and through the base 3. Upon the under side of the platform 5 is fixed an annular rack 8 with which meshes a pinion 9 fixed upon a shaft 10 journaled in a suitable bracket 11 upon the base 3. This shaft 10 is provided at its upper end with a hand wheel 12 by means of which it may be rotated for the purpose of turning the platform 5 to the desired position. The platform 5 supports the apparatus as a whole, as will be presently explained, and may be turned so as to permit of the water supply pipe of the apparatus being projected to either side of the truck.

Spaced supports 13 are fixed upon the platform 5 at opposite sides of the axis thereof. Mounted as at 14 for swinging movement upon each support 13 is a member 15 which constitutes the base of the 105 uprights upon which the support for the water supply pipe is adjustable. The uprights, above mentioned, are indicated by the numeral 16, and at their upper ends are connected by a cross beam 17. The 110 lower ends of the uprights are secured one to each of the base members 15, and near

their said lower ends the uprights are connected by cross members 18 which serve also as a support for the water supply pipe, in the manner to be presently explained.

5 Each member 15 is formed or provided with an arcuate rack 19 concentric to the pivot 14 about which it swings, and meshing with each of the racks 19 is a pinion 20 fixed upon the inner end of a shaft 21 journaled in a suitable bearing upon the corresponding support 13. A gear wheel 22 is also fixed upon each of the shafts 21 and meshes with a pinion 23 carried by a 10 shaft 24 also journaled upon the respective support 13. A gear wheel 25, upon the shaft 24, is in mesh with a pinion 26 fixed upon a short shaft 27 carrying a crank handle 28. By rotating both of the crank handles 28, simultaneously, the pinions 20 will be correspondingly rotated, and will impart swinging movement to the members 15 thereby raising or lowering the uprights 16.

The support for the water supply pipe 25 includes slides 29 and 30 which are slidably disposed against the uprights 16. A bracket 31 is supported upon the slide 29 and a bracket 32 is supported upon the slide 30. The support for the water supply pipe is 30 in the form of a head 33 having trunnions 34 projecting from opposite sides and journaled in the brackets 31 and 32, the head being in this manner supported for tilting movement. The water supply pipe is indicated by the numeral 35 and is slidably fitted through a bore 36 formed through said head 33. The head 33 carries a gear which is indicated by the numeral 37 and a pinion 38, upon a shaft 39, is in mesh with 35 the gear 37. This shaft 39 is journaled in the bracket 32 and the slide 30 upon which the said bracket is mounted and a double grooved pulley 40 is fixed upon the said shaft. A cross rod 41 extends from one to 40 the other of the members 15 and supports 45 a plate 42 located between the members. A rocker 43 is mounted upon the inner side of one of the members 15, and a similar rocker, indicated also by the numeral 43, is mounted upon one side of the plate 42. The member 15 is also formed with an arcuate slot 50 46 in which is slidably arranged a bearing 47, and a shaft 48 is journaled at its ends in the bearings 45 and 47 and carries a drum 49. A shaft 50 is journaled at its ends in 55 bearings in the said member 15, and the plate 42, and carries a drum 51, and cables 52 and 53 are wound upon the drums 49 and 51 respectively and are trained, in opposite directions, about the pulley 40. A gear 54 is carried by the shaft 48 and a gear

55 is carried by the shaft 50. A shaft 56 is journaled at its ends in the lower ends of the rockers 43, and one end of this shaft projects through an arcuate slot in the said member 15 and carries a gear 57 which is 60 at all times in mesh with the gear 54, and is adapted to be moved into and out of mesh with the gear 55, by means to be presently described. A shaft 58 is journaled in the said member 15 and plate 42 and carries a similar pinion 59 and a crank handle 60 by means of which handle it may be rotated. A lever 61 is pivoted as at 62 upon the said member 15 and is connected, by means of a link 63, at its lower end, with 67 the lower end of the rocker 43. A lever 64 is pivotally mounted, as at 65, upon the plate 42, and connected by means of a link 66 with the other rocker 43. A rack 67 is mounted upon the plate 42 and projects 72 rearwardly therefrom, and the lever 64 is engageable with one side of this rack and is held thereby at adjustment. A finger 68 is pivoted to the lever 61, and has a hooked end which is engageable in an opening 69 77 in the member 15, for the purpose of holding the lever 61 at adjustment when swung up, and a detent 70 is pivoted to the member 15 and is adapted to rest by gravity against the lever 61, when the lever is swung down, 82 for the purpose of holding it in this position. When both of the levers 61 and 64 are swung down to the position shown in Fig. 5 of the drawings, the gear 54 will be 87 out of mesh with the gear 55, and both of 92 these gears will be in mesh with the gear 57, the pinion 59 being in mesh with the said gear 57. Now, when the crank handle 60 is rotated, the drums 49 and 51 will be rotated in the same direction depending upon 97 the direction in which the crank handle is rotated, and when the crank handle is rotated in one direction, the cable 52 will be wound upon the drum 49 and the cable 53 will be unwound from the drum 51, rotation of the crank handle in the opposite direction resulting in the cable 53 being wound upon drum 51 and the cable 52 unwound from the drum 49. This will result in the pulley 40 being rotated in one 102 direction or the other, and this rotation of the pulley will act to angularly adjust the head 33, and correspondingly angularly adjust the water supply pipe 35.

When the levers 61 and 64 are swung up, 107 the gears 54 and 55 will be thrown into mesh with each other, and the gear 57 will then mesh with the gear 54 and will be moved out of mesh with the pinion 59. At the same time, the gear 57 is moved into mesh with a gear 71 which is fixed upon a shaft 72 journaled at its ends in the base members 15. At 112 this point it will be readily understood that when the gear 71 is rotated, the drums 49 and 51 will be caused to rotate toward or 117

away from each other, depending upon the direction of rotation of the said gear 71, and as a consequence the cables 52 and 53 will be wound upon and unwound from their respective drums. The function for this engagement of the gears will be presently made clear. A shaft 73 is also journaled in the base members 15 and carries drums 74 and pinions 75 and 76. Pinion 75 is in mesh with the gear 71 and the pinion 76 is in mesh with a gear 77 carried at the other end of the shaft 72. A crank handle 78 is fixed at each end of the shaft 73, and these crank handles are to be simultaneously rotated for the purpose of rotating said shaft. Cables 79 are wound upon the drums 74 and are trained about pulleys 80 loosely mounted upon a shaft 81 supported by the base members 15 and the plate 42. The cables are also trained over pulleys 82 which are mounted upon the cross bar 17 at the upper ends of the uprights 16, and are then connected to the brackets 31 and 32. It will now be understood that by rotating the shaft 73 by means of the crank handles 78, the cables 79 will be wound upon and unwound from their respective drums 74, and the slides 29 and 30 together with the water supply pipe supporting head 33 will be slid up or down upon the uprights 16, depending upon the direction of rotation of the said shaft 73. At this point it is also to be noted that when the levers 61 and 64 are swung up and the gear 57 is in mesh with the gear 71, as the shaft 73 rotates, the cables 52 and 53 will be unwound from or wound upon their respective drums so that when the shaft 73 is so rotated as to move the head 33 upwardly between the uprights 16, the cables 52 and 53 will be paid out from the drums 49 and 51, and when this head is lowered, the slack of the cables 52 and 53 will be taken up.

The other one of the base members 15 is formed with an arcuate slot indicated by the numeral 83, and the bearing 84 is slidably mounted in the slot and supports one end of the shaft 85, the other end of which shaft is journaled in the bearing 45. A drum 86 is fixed upon the shaft 85, and rockers 87 are mounted upon the said member 15 and the plate 42 and correspond in their location and relative arrangement to the rockers 43. A shaft 88 is journaled at its ends in the said base member 15 and the plate 42 and carries a drum 89, and journaled at its ends in the lower ends of the rockers 87 is a shaft 90 carrying a gear 91. The shaft 85 carries a gear 92 which is at all times in mesh with the gear 91, and the shaft 88 carries a gear 93 with which the gears 91 and 92 are adapted to mesh. The gear 77, heretofore referred to and described as being fixed upon the shaft 73, is adapted to mesh with the gear 91, as is also a pinion 94 fixed upon a shaft 95 which is in axial alinement with the

shaft 58 but rotates independently thereof. A crank handle 96 is fixed upon the shaft 95, and by this means the said shaft may be rotated to impart rotary movement to the train of gears above described. A lever 97 is pivotally mounted, as at 98, upon the said base member 15, and is connected by means of a link 99 with the shaft 90, and this lever carries a finger 100 having a hooked end adapted to engage in the opening 101 in the said member 15 for the purpose of holding the lever at adjustment when swung up. A pivoted detent 102 corresponding to the detent 70 is provided for holding the lever when swung down. A lever 103 is pivoted to the plate 42 and is engageable with the side of the rack 67 opposite the side with which the lever 64 co-operates, for the purpose of being held at adjustment when swung up or down.

When the levers 97 and 103 are swung down, the gear 91 will be in mesh with the gears 92 and 93, these two latter gears being out of mesh with each other, and the pinion 94 will be in mesh with the said gear 91. By rotating the shaft 95, rotary movement will be imparted to the shaft 92 and 93, and consequently to their respective drums 86 and 89, these drums being rotated in the same direction and in such manner as to wind or unwind cables 104 and 105, connected to them respectively. These cables 104 and 105 are trained over a double grooved pulley 106 mounted in the bracket 31 and extend in opposite directions and connect as at 107, to opposite ends of the water supply pipe 35. At this point it will be readily understood that with the levers 97, and 103 swung down, the crank handle may be rotated in one direction or the other to wind one cable and unwind the other, and thereby adjust the water supply pipe through the head 33. When it is desired to raise or lower the head 33, the levers 97 and 103 are to be swung up as well as the levers 61 and 64, and such movement of the levers 97 and 103 will result in the gear 91 being moved out of gear with the one 93, and into gear with the gear 77, the gear 91 being also moved out of gear with pinion 94. Rotation of the shaft 73 to the cable 79 thereon will then result in the rotation of the drums 86 and 89 toward or away from each other to pay out or take up the cables 104 and 105 as the head 33 is raised or lowered.

Pawl 108 rest in engagement with the gears 55 and 93 and serve to hold the said gears against backward rotation, and pawls 109 and 110 engage respectively with the pinions 75 and 76 and serve to prevent the shaft 73 rotating in a direction to unwind the cables 79 when the head 33 has been elevated.

Mounted upon the platform 5 is a water chest indicated by the numeral 111, and leading into this chest are a number of hose 130

112 through which water is to be supplied, these hose being preferably supplied by fire engines. Supply conduits 113 are connected by an elbow 114 at their lower ends to the 5 water chest 111 and extend upwardly from this chest in rear of the uprights 16. Conduits 116 and 117 are connected by a swivel elbow union 118, to each other, and the conduits 117 are connected by a like union 119 10 one to the upper end of each of the conduits 113. The rear end of the water supply pipe 35 is provided with a cap 120, and the conduits 116 are connected by swivel elbow joints 121 with the said cap at opposite sides 15 thereof.

From the foregoing description it will be understood that when the apparatus is collapsed, as illustrated in Fig. 2 of the drawings, the uprights 16 will lie substantially 20 horizontal, they being preferably supported near their free ends by a supporting bracket 122 mounted upon the truck frame 1. Due to the peculiar connection had between the several conduits 113, 116 and 117, and the 25 fact that the water supply pipe 35 is slidable through the head 33, the conduits may be folded to assume about the position shown in Fig. 2 of the drawings, and the water supply pipe be properly adjusted through 30 the head 33 by rotating the drums 86 and 89.

The operation of the apparatus is as follows, assuming that the apparatus is collapsed as illustrated in Fig. 2 of the drawings:—Crank handles 28 are rotated to 35 cause the base members 15 to swing from the position shown in Fig. 2 to the position shown in Fig. 6 of the drawings, and thereby swing the uprights 16 to vertical position. The platform 5 is then turned so that 40 the discharge end of the water supply pipe will be presented toward the burning building and the crank handles 78 are then rotated so as to wind up the cables 79 and elevate the head 33 to position opposite a 45 window of the building through which window the water supply pipe is to be projected. The levers 61, 64, 97 and 103 are at such time swung up. When the head 33 has been properly positioned, the drums 49 and 50 51 are so rotated as to properly angularly adjust the head 33 and correspondingly adjust the water supply pipe 35 so that its discharge end will be presented directly toward the window through which it is to be 55 projected. The drums 86 and 89 are then rotated to advance the water supply pipe to project it through the window. When the pipe has been so positioned, the water is supplied through the hose 112 and is discharged from the pipe 35 by way of nozzles 123 which project at different angles from a head 124 which is removably threaded upon the forward end of the pipe 35. It is preferable that the nozzles 123 be removable so 60 that they may be renewed when they become 65

burned or worn out. It will be understood that the levers 61, 64, 97 and 103 are all swung down while the drums 49 and 51 or the drums 86 and 89 are being rotated to angularly adjust the water supply pipe 35 70 or to advance or retract it.

Having thus described the invention what is claimed as new is:—

1. In apparatus of the class described, an upright, a support adjustable therealong, a 75 water supply pipe slidably carried by the support, a drum, a cable connected to the support and wound upon the drum, a pulley upon the support, a winding device, cables connected to the water supply pipe near its 80 opposite ends and trained over the pulley and connected with the winding device, a gear fixed with the drum, a gear fixed with the winding device, an operating shaft, a pinion carried thereby, a second operating 85 shaft, a pinion carried by the last mentioned shaft and meshing with the first mentioned gear, and a pinion movable into mesh with the first mentioned pinion and last mentioned gear and movable also into mesh with 90 the first mentioned gear.

2. In apparatus of the class described, a support, a winding drum, a cable connected to the support and to the drum to raise or lower the support when the drum is rotated 95 in one direction or the other, a water supply pipe carried by the support, a second winding drum, a cable connected to the water supply pipe and wound upon the last mentioned drum and arranged, when the said 100 last mentioned drum is rotated to move the pipe in the direction of its length upon the support, and means operable to rotate the first mentioned drum and simultaneously rotate the last mentioned drum to pay out or 105 take up the last mentioned cable.

3. In apparatus of the class described, a support mounted for up and down adjustment, a winding drum, a cable connected with the support and wound upon the drum whereby to raise or lower the support when the drum is rotated in one direction or the other, a water supply pipe mounted upon the support, a second drum, a cable wound thereon and arranged upon rotation of said 110 second mentioned drum to angularly adjust the support, and means for rotating the first mentioned drum and simultaneously rotating the last mentioned drum to pay out or 115 take up the last mentioned cable.

4. In apparatus of the class described, a frame, rockers mounted in the frame, a drum supported by the rockers, a gear fixed for rotation with the drum, a second drum carried in the frame, a gear fixed for rotation therewith, a support, a water supply pipe carried by the support, the support being mounted for angular adjustment, cables wound upon the drums in opposite directions and operatively connected to the sup- 120 125 130

port, a shaft mounted in the rockers, a gear carried by the shaft, an operating pinion, a winding drum, a cable connected to the support and wound upon the drum, means for 5 rotating the winding drum, and means for oscillating the rockers to move the first and second mentioned gears into mesh and the third mentioned gear into mesh with the last mentioned gear and out of mesh with the pinion, said means being operable to 10 oscillate the rockers to move the first mentioned gear out of mesh with the second mentioned gear and the third mentioned gear out of mesh with the last mentioned gear and into mesh with the first mentioned gear and the pinion.

5. In apparatus of the class described, a base, an upright mounted thereon, a support 20 vertically adjustable upon the upright, means upon the base connected with the said support for adjusting the same upon the upright, a head mounted for angular adjustment upon the support, means upon the base having operative connection with the head 25 and operable to angularly adjust the same, a water supply pipe slidably mounted through the head, a pulley upon the support, cables wound upon the pulley and connected at their ends to opposite ends of the water 30 supply pipe, and means upon the base for rotating the pulley.

6. In apparatus of the class described, an upright, a support vertically adjustable upon the upright, a head mounted for angular adjustment upon the support, a gear carried by the head at one side, a shaft journaled upon the support, a pinion fixed upon the shaft and meshing with the gear, a drum mounted upon the shaft, winding drums arranged for rotation in opposite directions, means for rotating the drums, a cable wound about the first mentioned drum and wound upon the winding drums, a pulley upon the upright, a shaft, a winding drum upon the shaft, means 45 for rotating the shaft, a cable wound upon the last mentioned winding drum and passed over said pulley and connected to the head, and gear connection between the last mentioned shaft and the first mentioned winding drums arranged to rotate the latter to 50 pay out the cables thereon when the shaft is rotated to wind up the last mentioned winding drum to vertically adjust the support upon the upright.

55 7. In apparatus of the class described, uprights mounted by one end for swinging movement in a vertical plane, a support movable on the uprights, a water supply pipe mounted upon the support and adapted 60 to be advanced and retracted through the support, and means operable from the base of the uprights for advancing and retracting said supply pipe.

8. In apparatus of the class described, 65 spaced uprights mounted for vertical swing-

ing movement, slides mounted for movement along the uprights, a head mounted between the slides for angular adjustment in a vertical plane, means for adjustably moving the slides upon the uprights, means for angularly adjusting the head with respect to the slides, a water supply pipe movably mounted through the head at a constant angle thereto, and means for advancing and retracting the water supply pipe through the head. 70 75

9. In apparatus of the class described, spaced uprights, a support mounted for vertical and angular adjustment between the uprights, a water supply pipe carried by the support and angularly adjustable therewith, 80 and means for advancing and retracting said pipe through its support and at any adjusted angle to the uprights.

10. In apparatus of the class described, an upright angularly adjustable in a vertical 85 plane, a support longitudinally adjustable thereon, a water supply pipe slidably mounted through the support, means for angularly adjusting the support whereby to angularly adjust the said supply pipe, and means for 90 advancing and retracting the said pipe.

11. In apparatus of the class described, uprights, a support manually movable vertically on the uprights, a water supply pipe movable through said support between the 95 uprights and at an angle thereto, and means for moving said pipe longitudinally.

12. In apparatus of the class described, uprights, a support movable upon the uprights, a supply pipe movable through said 100 support and extending at an angle to the uprights and from each side thereof, and means operable from the base of the uprights for moving said pipe both angularly, longitudinally and vertically. 105

13. An apparatus of the class described including a revolving base, uprights carried by the base and angularly adjustable in a vertical plane with respect thereto, a support mounted for movement along the uprights, 110 a supply pipe mounted for movement through the support, and means for reciprocating the supply pipe in the support.

14. In apparatus of the class described, a base, an upright mounted thereon, a support 115 vertically adjustable upon the upright, means upon the base connected with the said support for adjusting the same upon the upright, a head mounted for angular adjustment upon the support, means upon the base having operative connection with the head and operable to angularly adjust the same, a water supply pipe slidably mounted through the head, and means upon the base 120 having operative connection with the supply pipe for moving the same through the head. 125

15. In apparatus of the class described, a support mounted for up and down adjustment, a cable connected with the support, 130

means for winding and unwinding the cable to raise or lower the support, a water supply pipe mounted upon the support, a second cable operatively connected to the supply pipe to angularly adjust the same, means for winding and unwinding said second cable, and means operable by the actuation of the winding means of the first cable for simultaneously unwinding the second cable.

16. In apparatus of the class described, a support, a cable connected to the support, means for winding and unwinding the cable to raise or lower the support, a water supply pipe carried by the support, a second cable

operatively connected to the water supply pipe to move the same in the direction of its length upon the support when wound or unwound, means for winding or unwinding said second cable, and means operable by the actuation of the first winding means for simultaneously actuating the last winding means.

In testimony whereof, I affix my signature in presence of two witnesses.
